UNITED STATES PATENT OFFICE.

LAWRENCE W. LUELLEN, OF MOUNTAIN LAKES, NEW JERSEY.

RECEPTACLE.

Application filed January 2, 1917. Serial No. 140,041.

To all whom it may concern:

Be it known that I, LAWRENCE W. LUELLEN, a citizen of the United States, residing in Mountain Lakes, county of Morris, and 5 State of New Jersey, have invented certain new and useful Improvements in Receptacles, of which the following is a specification.

This invention relates to receptacles and particularly to shallow compartment receptacles adapted to be made out of cheap readily destrucible material, such as paper.

More specifically, my invention contemplates the provision of a paper receptacle of this character adapted either by itself or in 15 combination with a rigid supporting member or tray to be utilized as a service dish for food.

In restaurants and lunch rooms, a considerable item of expense is directly connected with the use of china dishes as these frequently break and chip and have to be replaced and they also require washing. As the latter is frequently merely a perfunctory process, they are moreover unsanitary.

25 Also, in many lunch rooms, the patrons are expected to wait upon themselves, the food being delivered to them at a counter and then carried by them to tables or arm chairs. This usually necessitates the handling by the 30 customer of a number of plates and dishes often at considerable inconvenience as the average customer lacks the skill of a professional waiter.

It is an object of the present invention 35 to provide a substitute for china plates and dishes which, while generally available in place of such dishes, finds particular utility as a service platter in restaurants and lunch rooms as it avoids the losses incident to 40 breakage of china-ware, obviates dish washing and simplifies the process of serving by providing a single vessel having several compartments in which the various viands constituting the meal may be separately contained.

45 It will be understood that a receptacle of the above character in order to be generally useful must be cheap so that it can be thrown away after a single use and it also must be tight so that the various juices and gravies will not leak onto the surface on which it is placed or into the holding tray. Both of these objects I may attain in various ways as by making the receptacle from a 55 single blank of paper which is brought to the required shape entirely by folding.

The nature of the invention will be better understood by reference to the accompanying drawings and the following detail description thereof which disclose one preferred embodiment of the invention as illustrative of the principle thereof and the best mode now known to me for carrying the same out. It will be understood, however, that the invention is not limited to 65 this embodiment nor is it limited to serving dishes or receptacle for food.

It is a further object of the invention to provide a light and inexpensive paper tray for containing a well balanced variety of 70 foods constituting a meal, the tray being preferably so constructed and of such a light material that it will be weighted down by the food and can be easily removed after the completion of a meal to be destroyed. With 75 this idea in mind the tray, of course, must contain a number of compartments, and in carrying out the invention the compartments are usually of different areas, one being preferably considerable larger than the other 80 and may be used as a plate for foods taken from the smaller compartments.

In the accompanying drawings, which form a part of this specification, Figure 1 is a plan view of the compartment receptacle, the holding tray being shown in dotted lines. Figure 2 is a transverse section through the receptacle and tray taken along the line of one of the partitions. Figure 3 is a section on line III—III of Figure 1. 90 Figure 4 is a view showing the side wall of the receptacle at a point where the partition joins it, the parts being shown partly folded. Figures 5, 6 and 7 are detailed plan views showing steps in the formation of a corner 95 of the side wall. Figure 8 is a plan view of the blank scored for folding, the dotted lines indicating the positions of what may be termed positive folds where the material is to be folded back upon itself or away 100 from the line so as to provide an apex or edge; while the dot and dash lines indicate negative folds where the paper is to be folded so as to provide a crease or groove with reference to the upper surface of the material. Figure 9 is a plan view of the permanent tray or holder. Figure 10 is a vertical section through the receptacle on the line X—X of Figure 1. Figure 11 is a fragmentary view of a modified form of 110 blank.

Referring to the drawings in detail, the

numeral 1 designates the temporary receptacle which is preferably formed of paper or other light and cheap material capable of being folded. This material is cut in 5 the form of a blank of suitable shape which may be a simple rectangle, as shown in Figure 8. If it is desired to provide a receptacle having a plurality of compartments such as one large compartment 2 and three small 10 compartments 3, 4 and 5 respectively, then the blank may be folded as indicated by the lines in Figure 8, the blank being preferably scored along these lines in the proper direction so as to facilitate folding. The 15 folding may be accomplished by hand or suitable machinery, preferably the latter. In order to form the side walls, the blank is scored along the lines 6 parallel to the edges and at each corner along divergent 20 lines 7 and 8. The edge portions of the blank outside of the lines 6 are bent upwardly to form the side walls 9, a positive fold being made at each corner along the line 7 and a negative fold along the line 8. 25 In this way a plait 10 is formed at the corner, as shown in Figure 5, the end portion 11 projecting beyond the upturned walls. This end portion is then folded or rolled over as indicated at 12 in Figures 30 6 and 7 and serves as a lock for preventing the plait from opening. In this way the side walls are retained in upturned position. Preferably the side walls are not turned up at right angles to the bottom but 35 flare outward somewhat as shown, the corners being more or less rounded as indicated in Figures 1 and 6.

When it is desired to provide compartments in the receptacle, then the blank will 40 be folded along transverse lines, two negative folds being made along spaced parallel lines, as indicated for instance at 13 in Figure 8, and a positive fold being made along an intermediate line 14. Where the partition joins the side walls, plaits are formed 45 by folding the paper entirely over upon itself along the section $a-b$ of the line 6 and by making positive folds along the lines 15 and 16 and a negative fold along 50 the line 17. These parts are then folded as indicated in Figures 1, 2, 3 and 4, resulting in the formation of a raised V-shaped partition extending across the receptacle and joining the side walls thereof. Where it is 55 desired to provide more than two compartments this may be accomplished by providing intersecting partitions as in the particular embodiment of the invention illustrated. The intersection of the partitions is 60 preferably constructed as follows:

The paper is folded over upon itself along the portions $c-d$, $d-e$, $e-f$ and $f-c$, respectively, of the intersecting pairs of lines 13 and sharp positive folds are given to the 65 paper along the short lines 18. The paper

is also given slight positive folds along the lines 19 forming the sides of a small square 20, which is placed diagonally with respect to the partitions. The paper is also folded slightly in a positive direction along the 70 short lines 21 extending between the points of intersection 22 of adjacent pairs of lines 18 and the corners of the square 20. In this way, it will be seen that plaits 23 are formed over the adjacent ends of the partitions and 75 a central box-like construction is provided having the top formed by the square 20, which is slightly raised above the apices of the partitions, the spaces between the square and the partition walls being occupied 80 by the pentagonal portions 24 (see Figures 1 and 10).

By forming a pair of intersecting partitions as illustrated, it will be seen that a receptacle having four compartments is provided and that by properly positioning the partitions, the proportions and the relative sizes of the compartments may be varied as desired. The arrangement shown is desirable for a serving dish in that a large 90 compartment 1 is provided, which may be utilized as a plate and in which the pièce de résistance may be served, while the various vegetables or condiments may be placed in the smaller compartments. It will be 95 understood, however, that the invention is not limited to the shape, number or arrangement of partitions or compartments shown or to a receptacle of rectangular or other specific configuration. 100

The receptacle may be used in such manner or may be of such stiff material as to be self supporting, but preferably for the purpose of cheapness, it is formed of light or thin paper and when used as a serving 105 dish is placed in a permanent tray or holder, such as illustrated in Figure 9 which may be formed of rigid material, such for instance, as papier mâché or metal. The tray illustrated comprises a flat bottom 40 having upturned side walls 41 which support the side walls of the receptacle. Preferably also the tray is provided with the abutments 42 which are shaped to engage 110 with the folds at the ends of the partitions 115 so as to firmly support the latter and prevent displacement of the parts of the receptacle. The tray with the paper receptacle therein, it will be seen forms a rigid structure which may be readily handled and which provides 120 the necessary compartments for receiving the various kinds of food. At the same time, the food itself is entirely contained within the paper receptacle and is out of contact with the tray so that the latter does 125 not require washing after each use but may be employed over again by removing the used paper receptacle which may be destroyed and replacing it with a new clean and sanitary receptacle. In this connection, 130

it is important to observe that by forming a paper receptacle in accordance with my invention, a structure is produced which is leak-proof as the paper blank is not cut and there are, therefore, no joints or openings through which leakage can take place. This feature permits the receptacle to be used to hold materials either of a solid or liquid character, for instance, my receptacle will 10 retain without leakage the gravies or juices of meats or vegetables.

The construction of my receptacle from a unitary blank of paper without cuts or openings therein not only prevents leakage 15 as above mentioned, but accomplishes this result without the use of any paste or other fastening means and in fact altogether avoids the use of such agencies. This reduces the cost of manufacture and also obviates the introduction of materials which 20 may be unsanitary such as glue or paste. Of course at times it may be found desirable to provide a separate paper receptacle for each compartment of the permanent tray or 25 holder.

From the foregoing it will be clear that the formation of the tray is in keeping with the predetermined idea or plan of furnishing a tray for restaurant use and which will 30 itself after the use by a single person compel its discard and thus prevent an unsanitary second use. The material will be of a character, of course, to resist wear and tear in this single service, incident the customary 35 employment of knives, forks or other utensils, but preferably not to permanently resist deterioration from the juices or liquids of the foods which would be expected to soften the paper and with the soiling or 40 smearing thereof by the food act in a self destroying manner, all working to prevent a repeated use of the tray, as stated. However, if desired, the receptacle may be formed of paper coated or impregnated with 45 paraffin or other suitable material of a water-proof and sanitary character, which will prevent the paper from softening, will stiffen the same and which may if desired be employed to cement the various folds and 50 plaits. The use of paraffin or other coating is not, however, in all cases necessary.

In Figure 11 I have shown a slight modification of my invention in which the blank is notched as indicated at 50 opposite the 55 ends of the partitions, thus eliminating the small triangular folds shown particularly in Figures 3 and 4. I prefer, however, in most cases to retain these folds as they strengthen the receptacle and notching of the blank is 60 also dispensed with.

While I have shown and described specifically only one preferred embodiment of my invention, this is to be understood as merely as illustrative thereof and I do not 65 desire to limit myself thereto but intend to

cover my invention in whatever form its principle may be embodied.

Having thus described my invention, I claim:

1. A receptacle of the character described 70 comprising a bottom, side walls and a partition folded upward from the bottom and united to the side walls entirely by folding without cutting the material.

2. A receptacle of the character described 75 composed of a relatively flexible non-metallic material having a bottom, integral side walls upturned therefrom and an inverted V-shaped partition folded upwardly from the bottom without cutting and united to 80 the side walls by uncut folds of the material.

3. A receptacle of the character described comprising a bottom, integral upturned side walls and a partition folded upwardly from the bottom, said partition being united to 85 the side walls by uncut folds of the material formed by folding the portions of the side wall adjacent to the ends of the partition over upon end portions of the partition and then outwardly. 90

4. A serving platter comprising the combination with a rigid tray, of a receptacle adapted to be removably held therein, said receptacle being formed from thin, cheap material and being provided with a plurality of compartments. 95

5. The combination with a receptacle formed by folding a single uncut blank of paper so as to provide a bottom, integral side walls and integral partitions, of a tray 100 of rigid material adapted to receive said receptacle and retain the same in shape.

6. The combination with a receptacle formed by folding a single uncut blank of paper so as to provide a bottom, integral 105 side walls and integral partitions, of a tray adapted to receive said receptacle and having side walls adapted to support the side walls of the receptacle and portions adapted to cooperate with the partitions to maintain 110 the same in position.

7. The combination with a receptacle including a bottom and inverted V-shaped partitions, of a tray adapted to hold said receptacle and having lugs cooperating with 115 the end portions of said V-shaped partitions.

8. The combination with a receptacle formed of a single blank of paper folded to provide integral upturned side walls and inverted V-shaped partitions, of a tray 120 adapted to receive said receptacle and having side walls engaging and supporting the side walls of said receptacle and having lugs cooperating with the inverted V-shaped partitions. 125

9. A tray having up-turned side walls and means within the tray and formed therewith adapted to enter into grooved portions of a light removable flexible paper lining for the tray to hold the latter in place. 130

10. A receptacle of the character described formed from a blank of material folded to form a bottom, side walls, and overlapping partitions dividing the receptacle into compartments. 5
11. A receptacle of the character described formed from a blank of material folded to form a bottom, side walls, and partitions extending upwardly from the bottom, said partitions overlapping to divide the receptacle into compartments and the ends of the partitions connected to the side walls by folding. 10
12. A receptacle of the character described formed from a blank of material folded to form a bottom, sides, and partitions extending upwardly from the bottom, the partitions being secured to and extending from the sides and overlapping at their meeting point. 15
13. A receptacle of the character described formed from a blank of material folded to form a bottom, sides, and partitions extending upwardly from the bottom, said partitions dividing the receptacle into compartments and folded, intermediate their ends, to overlap. 20
14. A receptacle of the character described formed from a blank of material folded to form a bottom, sides, and two partitions extending upwardly from the bottom, the partitions extending at right angles to one another and folded, intermediate their ends, to overlap at their meeting points. 25
15. A receptacle of the character described formed from a blank of material folded to form a bottom, sides, and partitions extending upwardly from the bottom, and dividing the receptacle into compartments, the partitions overlapping intermediate their ends and connected to the sides by folding. 30
16. A receptacle of the character described formed from a blank of material folded to form a bottom, sides, and overlapping partitions dividing the receptacle into compartments, the ends of the partitions being connected to the sides by folding the adjacent portions of the sides over the ends of the partitions. 35
17. A receptacle of the character described formed from a blank of material folded to form a bottom, sides, and inverted V-shaped partitions extending upwardly from the bottom and dividing the receptacle into compartments, said partitions being connected to the sides by folding the adjacent portions of the sides over the ends of the partitions. 40
18. A receptacle of the character described formed from a blank of material folded to form a bottom, sides, and inverted V-shaped partitions extending upwardly from the bottom and dividing the receptacle into compartments, said partitions being connected to the sides by folding the adjacent portions of the sides over the ends of the partitions. 45
19. A receptacle of the character described formed of a sheet of paper and comprising a bottom, side walls and a partition projecting upwardly from the bottom dividing it into predetermined varying sized compartments and united to the side walls entirely by displacing portions of the sheet without cutting the material, certain of the compartments being of a size to receive and confine such articles of food as served in an ordinary meal. 75
20. A receptacle of the character described composed of a relatively flexible non-metallic material having a bottom, integral side walls up-turned therefrom and double walled partitions of varying lengths projecting upwardly from the bottom to form varying sized compartments and united to the side walls by uncut portions of the material, certain of the compartments being of a size to receive and confine such articles of food as served in an ordinary meal. 80
21. The combination with a receptacle including a bottom and double walled partitions, of a tray adapted to hold said receptacle and having means cooperating with the said double walled partitions. 85
22. The combination with a receptacle formed of a single blank of paper displaced to provide integral up-turned side walls and double walled partitions, of a tray adapted to receive said receptacle and having side walls engaging and supporting the side walls of said receptacle and having means cooperating with the partitions. 90
23. A tray adapted for single meal service and similar purposes, formed of integral paper material capable of ready destruction, said integral material being shaped to provide bottom, side wall and partition portions forming compartments marginally confined by uncut portions of the material, certain of the compartments being of a size to receive and confine such articles of food as served in an ordinary meal. 100
24. A tray formed of paper comprising bottom, side wall and partition portions forming varying sized compartments, the side wall and partition portions being integral with the bottom and with each other to constitute the whole and uncut, unjointed, imperforate structure, certain of the compartments being of a size to receive and confine such articles of food as served in an ordinary meal. 110
25. A tray formed of paper comprising bottom, side wall and partition portions forming compartments of varying sizes in keeping with predetermined classes of foods 115

intended to constitute a meal, the side wall and partition portions being integral with the bottom and with each other to constitute the whole and uncut, unjointed, imperforate

5 structure, certain of the compartments being of a size to receive and confine such articles of food as served in an ordinary meal.

26. A tray formed of paper comprising bottom, side wall and partition portions

0 forming compartments of varying sizes in keeping with predetermined classes of foods intended to constitute a meal, the side wall and partition portions being so related to each other, and secured to the bottom, to effectually divide off and seal each of said varying compartments from the other, certain of the compartments being of a size to receive and confine such articles of food as served in an ordinary meal.

27. A tray adapted for single meal service formed of paper comprising bottom, side wall and partition portions forming compartments of varying sizes in keeping with predetermined classes of foods intended to

25 constitute a meal, the side wall and partition portions being so related to each other, and secured to the bottom, to effectually divide off and seal each of said varying compartments from the other, the paper being relatively thin and flexible to induce destruction of the tray following said single service.

28. A single service dining platter provided with varying sized compartment linings of thin cheap material which are to be

discarded after a single use, certain of the compartments being of a size to receive and confine such articles of food as served in an ordinary meal.

29. An individual dining service platter 40 comprising a plurality of different sized self-destructible food serving compartments held in a predetermined relation one to the other, certain of the compartments being of a size to receive and confine such articles of 45 food as served in an ordinary meal.

30. An individual dining service platter comprising a plurality of different sized self-destructible food serving compartments joined together, certain of the compartments 50 being of a size to receive and confine such articles of food as served in an ordinary meal.

31. An individual dining service platter made of one sheet of paper formed into a plurality of different sized self-destructible 55 food serving compartments for single use, certain of the compartments being of a size to receive and confine such articles of food as served in an ordinary meal.

32. A single service dining platter comprising a supporting member, and a plurality of readily destructible food serving compartments thereon, certain of the compartments being of a size to receive and confine such articles of food as served in an ordinary meal, the supporting member and compartments having mutually engageable portions to hold the latter in position. 60 65

LAWRENCE W. LUELLEN.
